UNITED STATES PATENT OFFICE.

STEPHEN S. ADAMS, OF ST. LOUIS, MISSOURI.

ENVELOPE.

Application filed May 9, 1922. Serial No. 559,528.

To all whom it may concern:

Be it known that I, STEPHEN S. ADAMS, a citizen of the United States, residing at St. Louis, Missouri, have invented a certain 5 new and useful Improvement in Envelopes, of which the following is a full, clear, and exact description, such as will enable others skilled in the art to which it appertains to make and use the same, reference being had 10 to the accompanying drawings, forming part of this application, in which—

Figure 1 is a view of my improved envelope, and

Figure 2 is an outline on a small scale of 15 the sheet from which the envelope is formed.

My invention relates to mailing devices and consists in an envelope especially adapted for sending a large article with which is enclosed a letter or other relatively small 20 article bearing an address which is visible through an opening in the envelope.

The main object of my invention is to locate the address bearing matter immovably in respect to the envelope opening or 25 "window."

An additional object is to provide such a construction so that the manufacture of the envelope will not require an undue amount 30 of material over and above that necessary for an ordinary envelope which does not possess the features provided in my invention.

In the accompanying drawings which illustrate a selected embodiment of my invention, the envelope 1 is designed to be used 35 in mailing automobile license plates accompanied by an owner's license card 2 or other similar certificate, and the name and address 3 on the card are revealed through the opening 4 in the envelope.

To hold the card 2 in the desired position in the envelope so that the device 3 will always be visible is the function of a slit 5 and a flap 6 preferably gummed on its underside. Slit 5 runs parallel with the lower folding line 7 of the envelope and is slightly longer than the length of card 2. The slit is spaced from folding line 7 a distance somewhat less than the width of card 2.

The flap 6 is provided on the edge 8 of the folded sheet forming the upper portion of the face of the envelope seam in Figure 1 and may be folded about the edge 8. The lefthand portion of flap 6 is shown in the position assumed when card 2 is being inserted into the envelope through slit 5. The

righthand portion of flap 6 is shown in the position assumed after the card is inserted when the gummed surface of the flap is moistened and stuck to the surface of the envelope.

Since the edges of the sheet from which the envelope is formed are pasted together so as to form a longitudinal seam 9 just above slit 5, it will be apparent that the sticking of flap 6 to the lower portion of the envelope as just described will effectively retain the card 2 against upward movement. As is apparent, the lower edge of the card is seated upon the lower folding line 7 of the envelope.

I am aware of other devices for retaining addressed matter of relatively small size within a much larger container, but such devices require an undue amount of surplus 75 material or additional elements which substantially increase the expense of the envelope and often render its use inconvenient and time-consuming.

I contemplate the usual modifications in 80 the details of my invention as may occur in its commercial development, and without departure from the spirit of the appended claims.

I claim:

1. In combination, an envelope having in one face a relatively short slit parallel with and spaced from one folding line of the envelope, a removable plane enclosure substantially smaller than the envelope, extending 90 through the slit and having one edge seated in said folding line, and means on said face for engaging the opposite edge of said enclosure to hold the latter against movement from the fold through the slit.

2. In combination, an envelope having in one face a relatively short slit, a removable plane enclosure substantially smaller than the envelope projecting through said slit and held thereby against shifting movement 100 longitudinally of the envelope, and means on said face of said envelope for temporarily preventing passage of said enclosure through said slit.

3. In combination, an envelope having in one face a relatively short slit parallel with and spaced from one folding line of the envelope, a plane enclosure substantially smaller than the envelope seated in the fold and extending through the slit, and means for holding said enclosure against movement 110 from the folding line through said slit com-

prising a flap secured to said face adjacent to one side of said slit and gummed on its undersurface so as to be attached to said face on the other side of said slit.

4. In combination, an envelope having a longitudinal seam, a slit in the under sheet near said seam, a plane enclosure projecting through said slit toward said seam, and a flap formed on the upper sheet adjacent to said seam and adapted to overlie said slit to prevent outward movement of said enclosure.

5. In combination, a rectangular envelope

having an opening across one edge, a flap for closing said opening, a slit in one face of said envelope extending in a direction transversely of said opening and parallel to a fold of said envelope, a plane enclosure substantially smaller than the envelope having one edge seated in said fold and extending through said slit, and a second flap engaging said face on opposite sides of said slit to retain said enclosure in said envelope.

In testimony whereof I hereunto affix my signature this 3rd day of May, 1922.

STEPHEN S. ADAMS.
